UNITED STATES PATENT OFFICE

2,597,331

ADJUSTABLE NOZZLE FOR COATING
MACHINES

Elmer B. Hurley, Chicago, Ill., assignor to Continental Can Company, Inc., New York, N. Y., a corporation of New York

Application May 15, 1947, Serial No. 748,207

5 Claims. (Cl. 299—133)

1

The following specification relates to improvements in adjustable nozzles for coating machines particularly adapted for applying a plastic lining in the groove or curl of a can end.

The invention will be understood best by reference to the machine for lining can ends disclosed in the patent granted Nelson Troyer et al. August 16, 1927, No. 1,639,118.

In such machines, can ends are successively presented to the nozzle of a coating mechanism by which the peripheral groove or curl of each can end is subjected to a jet of liquid coating composition. The coating composition is applied under pressure through a valve which is periodically opened to allow the composition to be deposited in the groove of the can end. Satisfactory operation demands instantaneous opening and closing of the valve and an exact timing to provide for two continuous coats to be applied during two revolutions of the can end. Any delay in opening the valve will leave an abnormally thin coated area at one point while delay in closing the valve at the conclusion of the coating operation results in the production of a tapering "tail" of the composition. This makes an abnormally thick spot in the coating and is also carried over the adjacent surface or edge of the can end. This uneven coating interferes with subsequent double seaming and efficient sealing of the end to the can body. The result of this is to cause coated can ends to adhere and prevents their normal feeding to cans. It also forms an undesirable smear on the surface of the ends.

As shown in the above mentioned patent, it is customary to mount the needle valve of the coating nozzle in a flexible diaphragm, usually a sheet of rubber through which the screw threaded shank of the needle valve is clamped by means of nuts. This flexible diaphragm of rubber-like material has a relatively short life. It may require replacement once every working day. One cause is the rapid flexing of the diaphragm by the needle valve. Another important cause of rapid deterioration has been the recent use of synthetic resinous coating compositions. These coating compositions contain solvents for example, lower aliphatic ketones, which seriously affect rubber and similar diaphragm materials.

It is an object of my invention to provide an improved nozzle for coating machines which shall have uniformity of operation throughout a long period of use.

It is a further object of my invention to prolong the effective life of these valve structures by utilizing diaphragm materials which shall be re-

sistant to the chemical action or softening effect of the solvents customarily present in resinous coating compositions.

Among the objects of my invention is to improve the precision of valve movement in both opening and closing operations free from the effect of a static load experienced wherever a flexible diaphragm is used.

A still further object of my invention is to permit the removal of the needle valve for repointing or replacement without dismantling the valve structure or removing its diaphragm.

Incidental to the last named object, it is found that the improved device permits close adjustment of the valve from outside the valve structure.

As already pointed out, the invention enables positive, instantaneous opening and closing of the needle valve without experiencing any lag in its movement. In this way the coating operation starts always at the same point in the cycle and the supply of coating composition is cut off positively at the end of the desired delivery period without producing any "tail" of excess liquid which would otherwise spread over the edge of the cover as it is being removed.

In order to illustrate the invention, I have shown my preferred form thereof by way of example on the accompanying drawing in which:

Fig. 1 is a side elevation of the improved coating nozzle and associated parts partly in section;

Fig. 2 is a bottom plan view of the improved diaphragm plate and

Fig. 3 is a side elevation of the needle valve and plate partly in section.

Broadly speaking, my invention consists in substituting a rigid, preferably metallic and non-corrosive partition for the usual resilient rubber-like diaphragm. The seal between the needle valve and the diaphragm is spaced away from the plane of their intersection, and the needle valve and partition are connected by an expansible resilient metallic bellows. Further, the needle valve is screw-threaded through the bellows in such a way as to permit ready adjustment of the valve and yet prevent material loss of the coating composition.

In the preferred form illustrated, I have shown the invention as applied to a can-end lining machine similar to that disclosed in the above mentioned patent to Troyer et al. Like the structure in said patent, I make use of a valve casing 5 having an inlet pipe 6 for the liquid coating composition which is delivered under pressure. As above stated, this compound may be a synthetic

resinous liquid having a wide range of viscosity. It may also contain any one of the usual solvents suitable for the purpose and which does not corrode ferrous metals.

The inlet pipe has a screw-threaded end 1. This carries a clamping ring 8 and an opposed clamping nut 9 by which the casing is mounted on the lining machine.

I have also shown a union nut 10 by which the inlet pipe is connected to the conduit supplying 10 the coating liquid.

Valve casing 5 has a valve chamber 11. The chamber has a tapering bottom ending in a discharge nipple 12. This nipple is screw-threaded as at 13. A conical valve tip 14 is clamped tightly to the end of the nipple 12 by means of a knurled nut 15.

The opposite upper end of the valve chamber 11 has a flange 16. A removable cap 17 is held on the flange 16 by means of bolts.

A collar 19 forms the upper portion of the cap 17 and is externally screw threaded as at 20. The collar 19 has an axial bore which holds a gasket 21 or similar packing. The gasket 21 is held down by the gland 22 and a nut 23 which is threaded on collar 19.

Needle valve 24 has its tapered head 25 fitting within the valve tip 14. The rear shank 26 of the needle valve 24 moves slidably in the packing 21 and gland 22. The needle valve has an intermediate screw-threaded portion 27 extending substantially through the valve chamber 11.

I have provided a rigid plate 28 to be seated between the upper flange 16 and the cap 17. This plate has a central opening 29 through which the needle valve 24 moves freely.

The bottom surface of the plate 28 carries a resilient metal bellows 30. The upper end of the bellows 30 is attached as by soldering to the plate 28 in a liquid tight manner.

The lower end of the bellows 30 carries a transverse disk 31 soldered or otherwise attached thereto in a liquid tight manner.

Disk 31 has an axial bore 32 which is screw-threaded to receive the intermediate threaded portion 27 of the needle valve.

The can-ends 32 are held in a chuck formed of opposed pads 33, 34. The chuck is brought into position with the curl 18 of the ends beneath and opposite the nozzle tip 14. The chuck is rotated rapidly for two revolutions and the needle valve raised simultaneously. A thin spray of coating composition is deposited in the curl of the can end without producing any overlap or "tail." The operation is repeated for each can-end presented.

Movement of the needle valve is accommodated by expansion and contraction of the bellows. The plate 28 remains rigid. The bellows withstand rapid operation without noticeable deterioration and consequently has a much longer life than is the case with a rubber-like diaphragm. As the plate is not required to flex, the width of the chamber 11 may be diminished providing a more compact structure.

By replacing the resilient flexible rubber-like diaphragm, customarily used, with the plate 28, the bellows 30 and the disk 31, I am able to obtain greatly improved results. The relative stiffness of the plate 28 eliminates one cause of wear and greatly prolongs the life of the valve.

Resilient metal bellows have been found to operate satisfactorily for a considerably increased length of time. For example, in a device in which the rubber type diaphragm had a normal life of

about 7000 coating operations each involving a $\frac{1}{16}$ " stroke, the metal bellows is estimated to be serviceable for over 500,000 similar operations.

Furthermore, the structure made exclusively of metal withstands satisfactorily any corrosive or solvent effect of the materials found in the liquid coating composition.

The screw threaded engagement between the disk and the needle valve is reasonably liquid tight. In addition, this makes possible the removal of the needle valve to correct for wear on its tapered point or for the substitution of a new needle valve. It will be clearly apparent that minor adjustment in the opening and closing relation of the needle valve to the top can be obtained without dismantling the transverse plate 28.

By this means, the accuracy of coating is greatly improved. The deposit is found to have exactly 20 the desired circumferential extent without abnormal thin or thick portions and without leaving a "tail" of coating composition on the curl or adjacent parts of the end.

This particular type of valve is cam operated 25 and does not have a back up spring to take up any play in the cam linkage after the lifting pressure is removed. Because of this any play due to wear or misfit in the linkage will result in a sluggish return of the nozzle to the seated or closed position. The bellows is under compression when the valve is open and tends to return to its normal dimension with a spring-like force when the lifting pressure is removed. This force is sufficient to overcome any discrepancies in the cam linkage and will result in a sharp closing of the valve.

While I have shown the preferred form of my invention, it is to be clearly understood that it is not limited in proportions, materials or structural details other than by the terms of the following claims.

What I claim is:

1. A valve device comprising a casing having a valve chamber, an inlet and an outlet therefor, said outlet forming a valve seat, a cover for the chamber, a packed slide-bearing in the cover, a transverse partition having a central opening, a resilient bellows of chemical resisting material attached to the partition around the opening, an apertured disk on the opposite end of the bellows, and a needle-valve having a tapered end in the valve seat, and having a shank adjustably held by screw-threaded engagement with the disk of the bellows and projecting through the slide-bearing, said screw-threaded engagement comprising the sole means for securing the shank to the disk.

2. A valve device comprising a casing having a valve chamber, an inlet and an outlet therefor, said outlet forming a valve seat, a cover for the chamber, a packed slide-bearing in the cover, a transverse rigid metallic partition having a central opening, a bellows of resilient metal attached to the partition around the opening, an apertured disk on the opposite end of the bellows, and a needle-valve having a tapered end in the valve seat, and having a shank adjustably held in screw-threaded engagement with the disk of the bellows and projecting through the slide-bearing.

3. A valve device comprising a casing having a valve chamber, an inlet and an outlet therefor, said outlet forming a valve seat, a cover for the chamber, a packed slide-bearing in the cover,

a transverse rigid metallic partition having a central opening, a bellows of resilient metal attached to the partition around the opening, a disk on the opposite end of the bellows and having a central screw-threaded aperture, and a needle-valve having a tapered end in the valve seat, having a screw-threaded intermediate portion adjustable through the aperture of the disk and in screw-threaded engagement with the disk and having a shank projecting through the slide-bearing, said screw-threaded engagement comprising the sole means for securing the shank to the disk.

4. A valve device comprising a casing having a valve chamber, an inlet and an outlet therefor, said outlet forming a valve seat, a cover for the chamber, a packed slide-bearing in the cover, a transverse rigid metallic partition having a central opening, an expandable metallic bellows attached to the partition around the opening, an apertured disk on the opposite end of the bellows, and a needle-valve having a tapered end in the valve seat and having a shank adjustably held in screw-threaded engagement with the disk of the bellows and projecting through the slide-bearing, said screw-threaded engagement comprising the sole means for securing the shank to the disk.

5. A valve device comprising a casing having a valve chamber, an inlet and an outlet therefor, said outlet forming a valve seat, a cover for

the chamber, a packed slide-bearing in the cover, a transverse rigid metallic partition having a central opening, a bellows of resilient metal attached to the partition around the opening and extending toward the chamber outlet, an apertured disk on the end of the bellows nearer the outlet, and a needle-valve having a tapered end receivable in the valve seat, and having a shank adjustably held in screw-threaded engagement with the disk of the bellows and having its opposite end projecting slidably through the slide-bearing, said screw-threaded engagement comprising the sole means for securing the shank to the disk.
